United States Patent Office.

J. J. GROSHANS, OF BUFFALO, NEW YORK.

Letters Patent No. 89,215, dated April 20, 1869.

IMPROVEMENT IN COUNTING REGISTER FOR PAPER-RULING MACHINES.

The Schedule referred to in these Letters Patent and making part of the same.

To all whom it may concern:

Be it known that I, J. J. GROSHANS, of Buffalo, in the county of Erie, and State of New York, have invented a certain new and useful Improvement in Indicators for Paper-Ruling Machines; and I do hereby declare that the following is a full and exact description thereof, reference being had to the accompanying drawings, making part of this specification.

Figure 1 is a perspective view of the whole device, with contrivance for fastening to a ruling-machine.

Figure 2 is a view of the indicating parts, with the back of the case removed.

Like letters of reference indicate corresponding parts in both figures.

My invention consists in providing an indicator, attached to a ruling-machine, that will automatically count the sheets as fast as they are ruled, and register the number of them on the dial of the same, as will be hereinafter fully explained.

In the drawings—

A represents the case of the indicator, having a dial-plate, B, the outer circle of figures being marked from 1 to 100, and the smaller, 1 to 10, both having index-hands, *a* representing the larger, and *b* the smaller.

The large hand, *a*, is set on a pin, *c*, which passes through a wheel, *C*, (inside the case, as shown in fig. 2,) having just one hundred teeth to correspond with the marks on the large circle of the dial-plate.

On one of the arms or spokes of the wheel is set an outwardly-projecting pin, *d*, which, on each revolution of the wheel, comes in contact with a single tooth of a small wheel, *D*, having ten teeth, said wheel running in frame *e*, which is firmly attached, at its upper end, to a frame-piece, *E*, in which runs the pivot *c* of the large wheel *C*.

An arm, *G*, is attached to the inside of the back, *F*, of the case, and extends down below said case.

To this is pivoted, at *f*, a lever, *g*, having, at its lower end, a finger, *h*.

This finger projects down just below a projecting grooved cam-wheel, *i*, running in frame *j*, attached to end of arm *G*.

A pawl, *k*, is pivoted to the top of lever *g*, and is kept up in contact with the teeth of the large wheel by means of spring *l*.

Another spring, *m*, is fastened to the lower part of the lever, to throw it back when it has been pressed forward.

A stop, *n*, is set just above the pivot *f*, to prevent the lever from going too far back.

A spring pawl, *H*, keeps the wheel *C* in place, after it has been moved forward.

I and *J* are the standard and rod, by which the indicator is fastened to a ruling-machine, the rod *J*, at its upper or bent end, setting into a socket at the back

of the indicator, a thumb-screw allowing it to be adjusted up or down, as required.

The operation is as follows:

As each sheet of paper passes out from the ruling-machine, its edge strikes against the extreme end of finger *h*, as shown in red lines, pressing it and the spring *m* back into the groove of wheel *i*, where it rests until the sheet passes entirely out, when the finger, by means of said spring *m*, is thrown back into place, ready for the next sheet.

As the finger *h* is pressed back, it pushes the upper end of lever *g* forward, which forces the pawl *k* against the tooth it rests against, and pushes the wheel forward just one tooth. This turns the large index-hand *a* forward just one mark on the dial, indicating one sheet is going through.

As soon as the sheet has passed out, and the finger *h* disengaged, it flies back in place and releases the pawl *k*, which slides back to next tooth, where it is kept by spring *l* pressed against said tooth, until the next sheet strikes the finger, which presses the wheel forward another tooth, as before described, while the spring pawl *H* prevents the wheel from falling back.

When one hundred sheets have passed and been registered, the pin *d* strikes against and turns one tooth of the small wheel *D*, the pin of which projects through the dial-plate, and moves the index-hand *b*, and carries it forward just one point, each point indicating one hundred.

The operation is certain and simple, and saves a great deal of time and labor in counting by hand, as is now done.

This indicator differs from those for other purposes, inasmuch as the parts require a special construction and arrangement to adapt them to be acted upon by a thin sheet of paper. The finger *h* and spring *m* are essential to accomplish this result.

What I claim as my invention, and desire to secure by Letters Patent, is—

1. For the purposes of an indicator for paper-ruling machines, the spring finger *h*, having its lower end free, and adapted to be struck by the paper, and its upper end carrying a spring pawl, substantially as described.

2. In combination therewith, the grooved wheel *i*, substantially as and for the purpose described.

3. In combination with the spring finger *h*, the toothed wheels *C* *D*, pin *d*, and hands *a* and *b*, substantially as and for the purpose described.

In witness whereof, I have hereunto signed my name in the presence of two subscribing witnesses.

J. J. GROSHANS.
